US00D770505S

(12) **United States Design Patent** (10) **Patent No.:** **US D770,505 S**
Bull et al. (45) **Date of Patent:** ** *Nov. 1, 2016

- (54) **DISPLAY SCREEN OR PORTION THEREOF WITH GRAPHICAL USER INTERFACE**
- (71) Applicant: **Apple Inc.**, Cupertino, CA (US)
- (72) Inventors: **William Bull**, Campbell, CA (US); **Kourtny Hicks**, Sunnyvale, CA (US); **Eric Hope**, Duvall, WA (US); **Policarpo Wood**, San Jose, CA (US)
- (73) Assignee: **Apple Inc.**, Cupertino, CA (US)
- (*) Notice: This patent is subject to a terminal disclaimer.
- (**) Term: **14 Years**
- (21) Appl. No.: **29/525,138**
- (22) Filed: **Apr. 27, 2015**

CLAIM

The ornamental design for a display screen or portion thereof with graphical user interface, as shown and described.

DESCRIPTION

The file of this patent contains at least one drawing executed in color. Copies of this patent publication with color drawing(s) will be provided by the Office upon request and payment of the necessary fee.

The FIGURE is a front view of a display screen or portion thereof with graphical user interface showing the claimed design.

The dashed broken lines in the figure show a display screen or portion thereof, and form no part of the claimed design.

1 Claim, 1 Drawing Sheet
(1 of 1 Drawing Sheet(s) Filed in Color)
